PRODUCTION OF ESTERS OF SUBSTITUTED
ALLYL ALCOHOLSJohn J. Ritter, Yonkers, N. Y., and Edward J. Kenney,
Springdale, Conn.No Drawing. Application July 27, 1953,
Serial No. 370,684

9 Claims. (Cl. 260—491)

This invention relates generally to processes for making organic chemical compounds, more particularly certain organic carboxylic acid esters of unsaturated aliphatic and unsaturated aromatic alcohols, and novel chemical compounds obtainable by these processes. These chemical compounds, because of their desirable odors and flavors, are useful in the manufacture of perfumes and certain of the compounds may be useful also in insect control and food flavoring.

It is well known that esters of aryl-substituted allyl alcohols, especially the esters of cinnamyl alcohol, are possessed of pleasant odors and other properties that make them outstandingly important substances for use in the compounding of perfumes, aromatic essences and food flavoring compositions. However, according to present-day methods of manufacture, the cost of producing these esters is high, resulting in the products being costly, thus limiting their use in commercial preparations. These manufacturing methods have the disadvantages of requiring very expensive starting materials, of involving chemical reactions that are extremely difficult to control, and of being substantially inoperative for the synthesis of aliphatic unsaturated alcohol esters, which are desirable and useful products.

These prior art methods are illustrated by the process now used for the manufacture of cinnamyl acetate. The starting material used is benzaldehyde which is reacted with acetaldehyde in the presence of caustic soda to effect an aldol condensation with formation of cinnamic aldehyde as the chief reaction product. The yield in this operation is not high, due in part to competing side reactions and this fact, in addition to the cost of the benzaldehyde required as starting material, makes cinnamic aldehyde an expensive substance.

When the cinnamic aldehyde intermediate has been obtained in the manner described, it is reduced to cinnamyl alcohol by treatment with aluminum isopropoxide or a similar reducing agent that can effect reduction of the aldehyde carbonyl group to yield the desired carbinol without attacking the double bond of the allyl chain. This reaction using aluminum isopropoxide involves initial formation of an addition product:

which subsequently breaks down to yield the desired alcohol. The comparative inefficiency of this method and the relatively unsatisfactory yields of cinnamic alcohol obtained serve further to increase the cost of the final products. As the final step in the prior art process, the cinnamic alcohol is esterified, by conventional methods, to yield the desired esters.

An object of the present invention is to provide methods for producing certain carboxylic acid esters of unsaturated aliphatic and unsaturated aromatic alcohols, particularly cinnamyl alcohol esters, which utilize inexpensive and commonly available starting materials, whereby these esters can be produced efficiently and at materially reduced costs.

Another object of the invention is to provide methods for making these esters without use of a cinnamyl alcohol as an intermediate.

5 A further object of the invention is to provide processes for making cinnamyl alcohol esters that are free of the disadvantages, above-mentioned, that are characteristic of the methods presently employed for making the esters.

Other objects, advantages and features of the processes of this invention will be obvious to those skilled in the 10 chemical arts from the following description of the invention.

In accordance with this invention, substituted allyl alcohol esters of organic carboxylic acids are obtained by pyrolysis of certain organic carboxylic acid esters of a 15 selected 3-acyloxymethoxy-propanol, preferably in the presence of an acid catalyst and at a subatmospheric pressure. The 3-acyloxymethoxy-propyl esters used as starting materials may be readily obtained by ring fission of substituted 1,3-dioxanes obtainable by reacting selected 20 aliphatic or aromatic aldehydes with olefins in the presence of an acid catalyst, or the esters may be obtained by other routes of organic synthesis as will be apparent to those skilled in the chemical arts.

According to the presently preferred embodiment of 25 this invention, the 3-acyloxymethoxy-propyl esters are prepared by reacting an alkene or aralkene, selected as hereinafter specified, with a selected aliphatic or aromatic aldehyde in the presence of an acid catalyst to yield a 30 substituted 1,3-dioxane intermediate product, which then is treated with a selected organic carboxylic acid anhydride to effect fission of the dioxane ring and formation of an intermediate carboxylic acid ester of a 3-acyloxymethoxy-propanol.

35 Illustrative of the alkenes that may be used in production of 1,3-dioxanes are:

55 Illustrative of the aralkenes that may be used in production of 1,3-dioxanes are:

70 Although each of the foregoing alkenes and aralkenes is functionally operative in the production of intermediate materials for use in the practice of this invention and,

when so utilized, yields final products useful in the perfumery, the intermediate products obtained from the aralkenes, particularly styrene, are especially desirable.

The selected alkene or aralkene is initially reacted, in the presence of an acid catalyst, with an aldehyde, preferably formaldehyde, to yield, as an intermediate product, a substituted 1,3-dioxane, which subsequently is subjected to esterification and pyrolysis to produce the desired unsaturated alcohol esters. Among the aliphatic aldehydes that may be used instead of the preferred formaldehyde in these operations are the saturated alkanals comprising at most 7 carbon atoms, of which acetaldehyde, propionaldehyde, butyraldehyde and heptaldehyde are preferred. Benzaldehyde is an aromatic aldehyde that may be used in the process of this invention.

When the alkene or aralkene above specified is reacted with an aldehyde selected from the mentioned group, the 1,3-dioxane product obtained is a compound of the formula:

wherein:

R_1 is a lower alkyl group comprising at most 6 carbon atoms or an aromatic radical chosen from the group consisting of phenyl and tolyl;
 R_2 and R_3 are hydrogen or methyl, not necessarily the same; and
 R_4 is hydrogen, a lower alkyl group comprising most 6 carbon atoms, or phenyl.

The intermediate 1,3-dioxane compound obtained as above described is treated with a selected organic carboxylic acid anhydride, in the presence of an acid catalyst such as sulfuric acid, to effect scission of the dioxane ring according to reactions that may be represented generally as follows:

wherein R_5 and R_6 , not necessarily the same, are chosen from the group consisting of lower alkyl groups comprising at most 3 carbon atoms and phenyl radicals.

For convenience, this cleavage of the dioxane ring by treatment with a selected anhydride of an organic carboxylic acid anhydride is herein referred to as acylolysis.

The preferred reagents for effecting acylolysis are the anhydrides of the lower alkanoic acids comprising, in the acid radical, at most 4 carbon atoms, such as acetic anhydride, which is especially satisfactory, propionic anhydride, butyric anhydride and the like. However, if desired, other carboxylic acid anhydrides may be used, such as benzoic acid anhydride, benzoic-acetic anhydride and the like.

It is preferable, although not essential, that the acylolysis reaction mixture, throughout the period when the reaction takes place, be maintained at a temperature merely slightly warmer than room temperature, say at a temperature within the range of about 30° C. to about 40° C., or higher, depending upon the structure and molecular weight of the compounds being used. As the reaction is exothermic, this temperature control is effected by agitating and cooling of the mixture.

When the reagents and the reaction products have reached a state of stable equilibrium, the reaction mixture is treated with an alkaline reagent to eliminate the acid catalyst present. It is preferred, although not essential, that the alkaline reagent for this purpose be an alkali metal salt of that organic carboxylic acid of which the anhydride was used in the acylolysis reaction, for example, sodium acetate when acetic anhydride was used. Following the treatment of the mixture with the alkaline re-

agent, the separated alkali metal sulfate is removed, for instance by filtering the mixture, and the acylolysis cleavage products, which remain in the filtrate, are further processed as now will be described.

For convenience, herein, these intermediate products obtained by the acylolysis of the dioxane intermediates will be designated 3-acyloxymethoxy-propyl esters with the understanding that this term signifies the variously substituted compounds of this basic formula as above set forth.

These last-mentioned intermediates, in accordance with this invention, are now subjected to pyrolysis whereby the γ -position substituent group is removed with a hydrogen atom from the β -position, with formation of a carbon-carbon double bond in the β - γ positions of the propanol chain (i. e., formation of a substituted allyl alcohol carboxylic acid ester). This pyrolytic reaction may be represented generally as follows:

wherein R_1 , R_2 , R_3 , R_4 , R_5 and R_6 have the significance aforesaid.

This pyrolysis of these substituted 3-acyloxymethoxy-propanol carboxylic acid esters to correspondingly substituted allyl alcohol esters can be effected by heat, merely, at temperatures within the range of about 150° C. to about 300° C. at a sufficiently reduced pressure, say of the order of about 0.5 to at most about 50 millimeters of mercury, that the volatile pyrolysis products are rapidly distilled from the zone where the pyrolysis occurs. Although this temperature range for the pyrolysis step defines the operative conditions, below which no satisfactory yields of the desired products are obtained and above which undesirable other reactions and charring of the materials occur, it will be understood that the pyrolysis temperature is functionally related to the pressure employed and hence may be varied in relationship thereto as will be understood by those versed in the chemical arts. Moreover, with the compounds of higher molecular weight, operations obviously should be conducted at somewhat higher temperatures and lower pressures, than are suitable for lower molecular weight compounds. In general, however, with compounds of average molecular weight, say when R_1 is phenyl, R_2 , R_3 and R_4 are hydrogen, and R_5 and R_6 are methyl, it is preferred that the pyrolysis be performed at temperatures within the range of 180° C. to 220° C. at 20 to 50 millimeters pressure, as these conditions, experience indicates, give optimum yields of the desired products.

Although, as above mentioned, the pyrolysis of the substituted 3-acyloxymethoxy-propanol carboxylic acid esters to correspondingly substituted allyl alcohol esters can be effected by heat, merely, at temperatures within the ranges specified, it has been found that the desired reaction proceeds much more efficiently in the presence of an acid catalyst. This catalyst is a relatively non-volatile acidic substance, such as a mineral acid, for instance, orthophosphoric acid or sulfuric acid, but preferably is an acid-reacting alkali-metal salt of such an acid, say sodium or potassium bisulfate; or it can be an organic sulfonic acid, either aliphatic or aromatic, of which benzene-sulfonic acid, p-toluenesulfonic acid, m-xylenesulfonic acid and hexanesulfonic acid are representative operative examples. The term "relatively non-volatile acidic substance," as here employed, signifies a substance that is not significantly volatilized from the reaction mixture under the specified reaction conditions.

The desired substituted allyl alcohol ester products are recovered from the pyrolysis distillate by removing the other reaction products present, the aldehyde and carboxylic acid, by usual methods, for instance by water

washing when low molecular weight aldehydes are used. The esters are substantially water insoluble.

From the foregoing, it will be apparent that the processes of this invention may be represented, in general terms, as follows, wherein the variants of the formulae (R₁, R₂, R₃, R₄, R₅ and R₆) have the significance above set forth:

It will be understood that the processes of this invention also may be utilized in the production of the aliphatic or aromatic alcohols that are represented by the formula:

which may be obtained readily from the esters, prepared as aforesaid, merely by hydrolysis according to known methods generally applicable to carboxylic acid esters.

To facilitate a better understanding of the principles of this invention, certain examples follow wherein the preparation of specific compounds by the processes of the invention will be described. It will be understood that these examples are provided for purposes of illustration merely and are not to be construed as constituting any limitations upon the scope of the invention defined by the claims.

EXAMPLE 1

Synthesis of cinnamyl acetate

Styrene is reacted with a twice-molecular proportion of

formaldehyde in an aqueous sulfuric acid reaction medium. The reaction may be accelerated by heating the mixture, say about 90° C., if desired, and the reaction product, 4-phenyl-1,3-dioxane, is recovered from the mixture by conventional methods. About 410 grams (ca. 2.5 moles) of this reaction product is subjected to acylolysis by treatment with 275 grams (2.7 moles) of acetic anhydride and about 3 grams of concentrated sulfuric acid. Preferably, the sulfuric acid and the acetic anhydride are mixed prior to addition and the mixture is added to the dioxane portionwise over a period of 15 to 20 minutes while agitating the mixture and applying cooling to maintain the temperature of the mixture within the range of about 30° C. to about 40° C. The reaction product here formed is 3-phenyl-2-oxa-1,5-pentanediol diacetate. After the initial exothermic reaction following addition of the acid mixture has subsided, the acylolysis reaction mixture

is permitted to stand at room temperature for a period of approximately 12 hours, then the sulfuric acid present is rendered ineffective by addition of about 20 grams of anhydrous sodium acetate, which causes formation and separation, from the mixture, of sodium sulfate. The separated salt may be removed by filtration and the filtrate, or the gross acylolysis product, is introduced, portionwise over a period of about 1 hour, into a vacuum stillpot containing approximately 10 grams of fused potassium bisulfate. The stillpot temperature is maintained at about 200° C. to 220° C. and the vacuum at about 19 to 22 millimeters of mercury throughout the addition period. By means of a suitable fractionating column fitted to the stillpot, a fraction boiling at 146° C. to 149° C. (at a pressure of 18 millimeters of mercury) is continuously collected and it is found to be cinnamyl acetate (saponification equivalent of the dried, neutralized material: found, 176.3; calculated, 176.1). About 292 grams of the ester is obtained, representing approximately 66.3% of the calculated yield.

EXAMPLE 2

The operations described in Example 1 are repeated except that the potassium bisulfate there employed is replaced with an equal weight of p-toluenesulfonic acid. In this manner, the cinnamyl acetate product (saponification equivalent: found, 173.8; calculated, 176.1) is obtained in an improved yield: about 308 grams (70% of calculated).

EXAMPLE 3

The operations described in Example 1 are repeated except that after the intermediate reaction mixture is treated with anhydrous sodium acetate and the treated mixture filtered, it is thereafter subjected to pyrolysis as follows: the acylolysis filtrate is introduced into the stillpot containing the fused potassium bisulfate, not portionwise, but, instead, in the full quantity, and the mixture is heated at about 200° C. at a pressure of approximately 50 millimeters of mercury. The distillate fraction boiling at about 172° C. to 177° C. (mainly, at 175° C. to 177° C.) at a pressure of approximately 43 millimeters of mercury substantially consists of cinnamyl acetate (saponification equivalent: found, 176.9; calculated, 176.1). The yield of the desired ester product is about 239 grams (about 54.4% of calculated).

EXAMPLE 4

Synthesis of 3,5,5-trimethyl-2-hexenyl acetate

About 672 grams (ca. 6 moles) of di-isobutylene and 360 grams (12 moles) of paraformaldehyde are mixed, 1 kilogram of aqueous sulfuric acid solution (25% by weight) is added and the mixture is stirred for 5 hours at room temperature, external cooling being applied initially to control the exothermic reaction that takes place. The reaction product, 4-methyl-4-neopentyl-1,3-dioxane, is obtained as a colorless supernatant oil, which is separated from the aqueous sulfuric acid layer, washed with water and aqueous soda solution, dried and distilled. The fraction boiling at 175° C. to 225° C. at atmospheric pressure is collected and this oil is then reacted with a mixture of acetic anhydride and sulfuric acid in substantially the same manner as is described as the acylolysis step in Example 1, and then the reaction mixture is treated with anhydrous sodium acetate to render the sulfuric acid present ineffective. After removing the

separated sodium sulfate, the acylolysis product, 3,5,5-trimethyl-3-acetoxymethoxy-hexyl acetate is subjected to pyrolysis in substantially the same manner as is described in Example 1, using fused potassium bisulfate, and the pyrolysis product, 3,5,5-trimethyl-2-hexenyl acetate, a hitherto unknown chemical compound is collected as the fraction boiling at 220° to 225° C. at atmospheric pressure. It is a colorless liquid having a floral or mildly fruity odor. It was conclusively identified by hydrolyzing it to the alcohol, oxidizing the alcohol to the aldehyde, treating the aldehyde with a weak base to effect a de-aldo reaction yielding acetaldehyde and the known methyl neopentyl ketone.

It will be obvious to those skilled in the chemical arts from the foregoing, that, in like manner, other 3,5,5-trimethyl-2-hexenyl esters of the lower alkanic acids, e. g., propionic and butyric acid, may be prepared by replacing the acetic anhydride employed in the acylolysis step with a different anhydride, e. g., propionic anhydride or butyric anhydride.

EXAMPLE 5

Synthesis of cinnamyl acetate by reduced pressure pyrolysis of 3-phenyl-2-oxa-1,5-pentanediol diacetate without use of catalyst

3-phenyl-2-oxa-1,5-pentanediol diacetate, which may be prepared as described in Example 1, is placed in a vacuum stillpot, the pressure is adjusted at about 50 millimeters of mercury and heat is applied to the stillpot. Rapid distillation quickly ensues as the head temperature reaches about 64° C.; at about 90° C., formaldehyde polymer begins to coat the condenser and receiver; and heating is continued until the pot temperature reaches about 138° C. (about 40 to 45 minutes). The collected distillate is diluted with water, the organic layer, after washing with water is taken up in benzene. The pot liquid is further distilled at 170° C. to 179° C., at a pressure of about 51 millimeters of mercury and this distillate, dissolved in benzene, is mixed with the benzene solution of the first fraction. The combined benzene solutions are washed successively with dilute aqueous ammonia solution, water, dilute acetic acid, and with water again, then the organic fraction is distilled at a pressure of 43 to 44 millimeters of mercury. The fraction boiling at 172° C. to 177° C. is collected and is found to be cinnamyl acetate (yield, 54.4% of calculated; saponification equivalent, calculated, 176.1, found, 176.9). When treated with aqueous sodium hydroxide solution, this ester product is hydrolyzed, yielding cinnamyl alcohol.

EXAMPLE 6

Synthesis of cinnamyl propionate

At a temperature of about 0° C., approximately 33.5 grams (0.25 mole) of propionic anhydride is added to 0.2 gram of concentrated sulfuric acid and this solution is added, portionwise over a period of 10 to 15 minutes, to 41 grams (0.25 mole) of 4-phenyl-1,3-dioxane, which may be obtained as described in Example 1. During the addition, external cooling is applied, if necessary, in order that the temperature of the reaction mixture is maintained below about 40° C. and, when the addition has been completed, the reaction mixture is allowed to stand over-

night at room temperature. The solution containing the reaction product, 3-phenyl-2-oxa-1,5-pentanediol di-propionate, is treated with 0.7 gram anhydrous sodium acetate, filtered and the filtrate is pyrolyzed, using fused potassium bisulfate as a catalyst, at a pressure of about 22 millimeters of mercury in a stillpot heated in an oil bath at 230° C. to 245° C. The collected distillate is neutralized with dilute sodium bicarbonate solution, extracted with benzene and the benzene extract is washed successively with dilute sulfuric acid and with water, then it is dried and the benzene is distilled off. By fractional distillation of the residue at a pressure of 1 millimeter of mercury and collection of the fraction that boils in the range 117° C. to 119° C. cinnamyl propionate is obtained (yield, equivalent to 46.1% of the calculated yield; saponification equivalent, calculated, 190.1, found, 190.6).

EXAMPLE 7

Synthesis of cinnamyl butyrate

To about 42 grams of butyric anhydride, chilled in an ice bath, is added with stirring, 0.3 grams of concentrated sulfuric acid, and this mixture is added, portionwise over a period of about 10 minutes, to 41 grams (0.25 mole) of 4-phenyl-1,3-dioxane. The mild exothermic reaction that ensues is controlled by external cooling, if necessary, so that the temperature of the reaction mixture does not rise above and, preferably is maintained within the range of about 30° C. to 40° C. The reaction mixture is allowed to stand overnight, then about 1 gram of sodium acetate is added to inactivate sulfuric acid present, the mixture is filtered to remove separated sodium sulfate and then the 3-phenyl-2-oxa-1,5-pentanediol dibutyrate is pyrolyzed as follows:

The diester is introduced slowly over a period of about 35 minutes, into a stillpot containing about 1.5 grams of fused potassium bisulfate, heated by an oil bath heated at 240° C. to 245° C. The stillpot pressure is maintained at about 17 to 18 millimeters of mercury. The heating of the pot is so controlled that the distillate temperature is about 160° C. after seven minutes operation and gradually rises to a maximum within the range of 155° C. to 165° C. The distillate is collected, dissolved in benzene, washed with water and dilute sodium bicarbonate solution, shaken with dilute sulfuric acid, washed again with water until the washings are neutral, and dried. The solvent is removed by distillation and the still residue is fractionally distilled at a vacuum of 1 millimeter of mercury. The fraction boiling at 124° C. to 126° C. is collected and is found to be cinnamyl butyrate, obtained in a yield of about 52% of the calculated (saponification equivalent, calculated, 204.1, found, 202.2).

It will be apparent to those versed in the art to which this invention relates that minor modifications may be made in the processes described without departing from the scope of the invention.

Having thus described the subject matter of the invention, what it is desired to secure by Letters Patent is:

1. The process for producing organic carboxylic acid esters of substituted allyl alcohols that comprises subjecting to pyrolysis, at a temperature within the range of about 150° C. to about 300° C. and at a reduced pres-

sure of at most about 50 millimeters of mercury, a compound represented by the formula

wherein R₁ is phenyl and R₂ and R₃ are radicals selected from the group consisting of alkyl groups comprising at most 3 carbon atoms and phenyl, and recovering from the pyrolysis mixture an ester of the formula

wherein R₁ and R₂ have the significance aforesaid.

2. The process for producing organic carboxylic acid esters of substituted allyl alcohols that comprises subjecting to pyrolysis, in the presence of a relatively non-volatile acidic catalyst at a temperature within the range of about 150° C. to about 300° C. and at a reduced pressure of at most about 50 millimeters of mercury, a compound represented by the formula

wherein R₁ is phenyl and R₂ and R₃ are radicals selected from the group consisting of alkyl groups comprising at most 3 carbon atoms and phenyl, and recovering from the pyrolysis mixture an ester of the formula

wherein R₁ and R₂ have the significance aforesaid.

3. The process defined in claim 2 wherein the relatively non-volatile acidic catalyst is potassium bisulfate.

4. The process defined in claim 2 wherein the relatively non-volatile acidic catalyst is p-toluenesulfonic acid.

5. The process defined in claim 2 wherein the relatively non-volatile acidic catalyst is potassium bisulfate and R₂ and R₃ are methyl.

10 6. The process defined in claim 2 wherein the relatively non-volatile acidic catalyst is p-toluenesulfonic acid and R₂ and R₃ are methyl.

7. The process defined in claim 2 wherein the relatively non-volatile acidic catalyst is potassium bisulfate and R₂ and R₃ are ethyl.

8. The process defined in claim 2 wherein the relatively non-volatile acidic catalyst is potassium bisulfate and R₂ and R₃ are n-propyl.

9. The process defined in claim 1 wherein R₂ and R₃ are methyl.
